UNITED STATES PATENT OFFICE.

ALBERT M. BULLARD, OF NEW YORK, N. Y., ASSIGNOR, BY MESNE ASSIGNMENTS, TO
WESTERN ELECTRIC COMPANY, INCORPORATED, A CORPORATION OF NEW YORK.

TELEPHONE-EXCHANGE SYSTEM AND APPARATUS THEREFOR.

1,219,700.

Specification of Letters Patent. Patented Mar. 20, 1917.

Application filed July 17, 1906. Serial No. 326,531.

To all whom it may concern:

Be it known that I, ALBERT M. BULLARD, residing at New York, in the county of New York and State of New York, have invented 5 certain new and useful Improvements in Telephone-Exchange Systems and Apparatus Therefor, of which the following is a specification.

My invention relates to an automatic 10 switching system for telephone exchanges, and its object is to provide an improved organization of circuits and apparatus whereby a line to which connection is desired may be selected with speed and accuracy; the apparatus required being comparatively simple and inexpensive, and adapted to secure the greatest reliability and efficiency of operation.

Another feature of my invention, which 20 has reference particularly to a "full automatic" system in which the selective connecting apparatus is controlled exclusively from the subscribers' stations, involves the use of a comparatively few automatic connecting devices, which may be seized for use by any one of a number of telephone lines. Mechanism is provided for constantly causing the idle connecting devices to be brought 25 successively into operative relation with the various lines of the exchange. The connecting devices are thus made available, one after another, for use by any line which chances to be calling, so that the calls are evenly distributed among them, the interval 30 during which a call is answered being reduced to a minimum, and there being no possibility of two devices taking up the same call.

Another feature contemplated by my invention is that of terminating the lines entering the exchange upon terminals so related to the interconnecting members of the switches which serve to establish communication between the various lines, that a 40 single set of terminals individual to a particular line is accessible to all of the connecting devices or automatic switches. By providing terminals of this character it not only becomes unnecessary to provide separate 45 terminals for each line upon each switch and connect these terminals together by "multiple" wiring; but, by so arranging the single group of terminals of the line adapted to be 50 engaged by all of the connecting devices or members that the group will be slightly dis-

placed in position when connection is completed with it by any of the connecting devices, it becomes possible to move the terminals bodily out of the possibility of engagement with any other of the connecting 60 members, thus preventing the establishment of connection between the engaged line and any other of the connecting members which might otherwise have access to it. The movement or displacement of the group of 65 terminals of each line common to all of the devices may also be utilized, as is done in the system of my invention, to so change the position of a part associated with the group of terminals with relation to the other connecting devices that a busy signal is automatically given when another of the connecting devices is moved into position to make connection with the engaged line.

By dispensing with connecting devices 70 permanently associated with and individual to each line, and substituting a lesser number of connecting devices common to a group of lines and made successively available to each line in the group, the circuits of 75 the lines are left normally open at both ends, and the place of the customarily employed line relay normally associated with and individual to each line is taken by magnets 80 associated with the common connecting devices or switches. These magnets control the associated connecting devices or switches in finding and making connection with a calling line, and in selecting and making connection with the line with which the calling line desires to communicate; and, by being included together with the common source of current in a bridge of the connecting circuit, they are also made to serve as 85 retardation coils to regulate the supply of 90 energizing current to the connected telephone lines and prevent the shunting of the voice currents.

My invention also involves a number of other features, and novel apparatus which 100 may be advantageously employed in practising the system of my invention, as will be particularly described in the following portions of the specification.

Before entering into a detailed description 105 of the apparatus and circuits employed in the system of my invention, in order that the system in its entirety may be more clearly comprehended I shall briefly outline its salient features as represented in the particular 110

embodiment employed in the present instance. At the center of a cylindrical group of line terminals, each of which consists of a number of parallel metallic rods vertically arranged, is supported a rotating shaft bearing a number of pairs of switch arms or connecting members loosely mounted thereon, but normally locked to the shaft by electromagnetically controlled keys. At the outer extremity of each pair of arms are contact springs adapted to be thrust forward, by electromagnets forming a part of said arms, into engagement with the vertical rods. Each pair of arms constitutes a complete connecting device corresponding, in effect, to a pair of connecting cords in a manual switch board. The arms of a pair are normally so locked to the shaft, each by its own key, that they lie in the same vertical plane and are revolved as one. One of the arms, the upper one in the present arrangement, bears a flexible spring which tests with a wiping contact each idle line in turn until it finds one wishing to make a call. That the line is calling is indicated by an altered electrical condition of its terminal brought about by the act of taking the telephone from the hook at the substation. To this altered electrical condition the magnets of the connecting arms are responsive, and when the wiping spring makes contact with the terminal the magnets operate to disengage both arms from the shaft and to cause one of them to make contact with the terminals of the calling line. The vertical line terminal rods are so mounted that when they are pressed upon by the connecting springs of the arm they are turned slightly upon a central supporting rod, and are thus withdrawn from the path of the test springs of all the other pairs of arms. Furthermore, this movement brings into prominence a terminal connected with the busy tone apparatus, which protects the line from being intruded upon.

The process of selecting the line with which connection is desired is effected by manually moving a device at the substation through a predetermined arc, corresponding with the degree of separation between the terminals of the calling and the terminals of the called line on the central office switch. This deenergizes the electromagnet of the lower arm and allows the latter to reengage the rotating shaft, whereupon it resumes its revolution, leaving the upper arm behind. In thus causing the arms to separate, the line current is changed to intermittent current by a device common to both arms. This current causes a reverse movement of the substation device until the latter returns to its normal position, when it causes the magnets of the lower arm again to become energized. This stops the lower arm opposite the line terminals of the desired subscriber, and causes the arm to make contact there-

with, provided the desired line is not already engaged. If it is engaged, the protruding busy tone terminal associated with the line prevents the magnet of the arm from operating to bring the connecting springs of the arm into contact with the line, and the busy tone signal is transmitted to the calling subscriber. The calling or selecting arm of the pair is arranged to reverse the connection of the common battery with the line of the called subscriber in making contact with the line terminals, and thus to cause a vibrating bell at the called station to ring until the subscriber answers.

When the subscribers hang up, the magnets of both arms are deenergized, and the keys of each are ready to reengage the slot in the shaft when next it passes beneath them. Pending this reengagement, each arm is held stationary by a fork which engages a fixed point in the cylinder of line rods until the key drops into place. The arrangement is such that a pair of connecting arms cannot be appropriated by a calling line until the arms, which have been moved apart in the act of establishing connection between two lines, have re-united.

I will describe my invention more particularly by reference to the accompanying drawings, wherein Figure 1 is a front elevation, with a portion of the face broken away, of the substation interrupter which I prefer to employ in the system of my invention; Fig. 2 is a side elevation of the interrupter, with a part of the case broken away to show the arrangement of the apparatus within; Fig. 3 is a front elevation of the automatic switchboard of my invention, with most of the line terminal rods broken away to show the pairs of connecting arms mounted in the interior; Fig. 4 is a top plan view of the automatic switchboard illustrated in Fig. 3; Fig. 5 is a side elevation of a single pair of connecting arms with associated groups of line terminals; Fig. 6 is a plan view of a pair of connecting arms; Fig. 7 is a plan view of the selector arm, or lower one of the pair of connecting arms; Fig. 8 is a plan view of the ends of the selector arm with its connecting springs at one end and its anchoring fork at the other, thrust into engagement with the corresponding groups of line terminals; Fig. 9 is an elevation of the anchoring ends of a pair of connecting arms; Fig. 10 is an end elevation of the connecting ends of a pair of arms; Fig. 11 is a plan view of the hub of the finder arm, or upper arm of the pair, with portions broken away; Fig. 12 is a like view of the hub of the lower or selector arm; Fig. 13 is a front elevation of the hubs of a pair of arms partially in section in the central vertical plane of the arms; Fig. 14 is a rear elevation of the hubs of a pair of arms, looking in the opposite direction.

from the view shown in Fig. 5; Fig. 15 is a diagrammatic representation of two subscribers' lines extending from their respective substations to the automatic switch board at the central office, all being equipped and arranged in accordance with the system of my invention; Fig. 16 illustrates the wiring of a pair of connecting arms employed in the system of my invention; Fig. 17 is a skeleton diagram illustrating certain elements of the specific system shown, which are involved in controlling the operation of a selector or traveler by a controller located at a distant point, which controller is in turn operated (to an extent which may be predetermined) by current impulses transmitted back to said controller by the selector or traveler in its advance.

Referring to Figs. 1 and 2, which represent the substation interrupter which I have devised and find convenient to employ in my automatic telephone system, and which is designated by the reference character a , the device comprises an inclosing box or case a^1 , within which is mounted the apparatus which constitutes the interrupter. This apparatus consists of a spur gear a^5 mounted upon a shaft a^3 which has bearings in a frame a^2 as secured to the front of the inclosing case a^1 . The shaft a^3 projects through the front of the case and carries a pointer arm a^4 , the extremity of which is adapted to be moved about the dial a^{16} , in the present instance, in fifty steps, the steps being indicated by the numerals 1 through 50. The spur gear a^5 engages a pinion a^6 mounted upon an arbor having its bearings in the frame a^2 and upon the arbor a star wheel a^7 is mounted. The star wheel is adapted to be rotated by the escapement lever a^8 which extends from and is moved by the armature a^9 of an electromagnet a^{11} suitably supported upon the frame. The armature a^9 is normally held in a retracted position away from the poles of the electromagnet by the spring a^{12} . The pointer arm a^4 is adapted to be moved by hand, together with the spur gear and star wheel associated with it through the shaft a^3 , and may be provided with a knob or handle a^{22} for that purpose. The angle of the teeth of the star wheel a^7 is sufficiently obtuse to allow the latter, and all parts associated with it, to be freely rotated in either direction between the teeth of the escapement lever a^8 by means of the pointer arm. The star wheel and the coöperating escapement lever are so related that when the magnet is caused to move the armature a^9 back and forth, the pointer arm is rotated in a contraclockwise direction.

Upon the shaft a^3 is mounted a head or commutator a^{13} . This commutator has a groove or depression cut in its periphery in which one of the members of the switch a^{15}

is normally adapted to lie. When the pointer arm and its associated parts are rotated from the position which they normally occupy, the switch member rides out of the depression, and is thrust into contact with the other member of the switch a^{15} , thus completing the circuit between them. The hub or commutator a^{13} is loosely mounted upon the shaft a^3 , but is normally held from rotating thereon by the set screw a^{14} . When desired, the angular relation of the groove in the commutator to the pointer arm may be altered by loosening the set screw and turning the commutator upon the shaft a^3 .

In using the interrupting mechanism described in the foregoing, the pointer arm normally rests opposite the number on the dial which represents the station with which the interrupter is associated. The commutator is secured by means of the set screw a^{14} in such angular relation to the pointer arm that the associated member of the switch a^{15} rests in the groove or depression. To set the device for calling any particular line in the exchange with which connection may be desired, the pointer arm is manually rotated by means of the handle a^{22} so that it rests opposite the number on the dial, which represents that line. When thus moved the commutator has been rotated with relation to the switch a^{15} so that the latter is caused to close its circuit. In the actuation of the connecting mechanism at the central office the circuit through the electro-magnet a^{11} of the interrupter, which circuit also includes the switch a^{15} , is intermittently completed and broken. The impulses of current thus produced actuate the armature a^9 of the magnet, and cause the escapement lever a^8 to return the pointer arm in a contra-clockwise direction toward its normal position, the pointer arm being returned one step for each impulse of current. When as many impulses have passed as the number of steps the arm has been moved from its home or normal position, the depression of the commutator a^{13} comes under the coöperating member of the switch a^{15} , and the switch operates to break the circuit and stop further movement.

Associated with the interrupter, and coöperating with it in the control of the circuit, is an electromagnet a^{21} suitably mounted beneath the interrupting mechanism above described, and in the same inclosing case. The armature a^{20} of this electromagnet is carried upon the plunger a^{18} of a push button a^{19} , which is adapted, through the medium of the plunger, to operate the switch a^{17} consisting of three contact springs, one of which is arranged normally to make contact with another, and to interrupt that contact and complete connection with the third spring when the plunger is moved by the depression of the push button a^{19} .

When the push button is moved to change the circuit through the switch a^{17} , the armature a^{20} is brought into contact with the poles of the electromagnet a^{21} , and the energizing current which flows through the magnet on account of the change in the circuit controlled by the switch a^{17} causes the armature to be attracted, and the key to be held in its operated position, until the circuit is interrupted at another point.

I will now describe the automatic switch mechanism illustrated in the drawing, Fig. 3 to Fig. 14, inclusive. The switching mechanism in its entirety is designated R and comprises a general framework built, in the present instance, in halves r , r^1 , each half comprising semi-circular segmental top and bottom plates r^2 , r^3 , and r^4 , r^5 , respectively, held together by the supporting rods r^6 . The halves r and r^1 of the framework are supported upon a base r^{20} , and are fulcrumed to swing upon supporting shafts r^{11} , r^{12} , which are firmly secured in the base r^{20} and extend up through one end of each of the halves of the framework. At the other extremity of each of the halves r , r^1 , are like rods r^7 , r^8 , which, however, do not extend into the base r^{20} , but merely serve to strengthen the framework. The extremities of the upper segments r^2 , r^4 are united by the bracing pieces r^{23} and r^{24} . Through the extremities of the halves r , r^1 , of the framework opposite the points where they are hinged or fulcrumed, locking pins r^9 , r^{10} extend, thus fastening the halves of the framework securely together.

Mounted in the halves r , r^1 of the framework, and pivoted at both ends in the top and bottom segmental portions r^2 , r^3 , r^4 , r^5 , respectively, are the groups of line terminals d . Each group comprises a number of metallic rods insulatedly mounted at the top and bottom in the plates d^{11} , which carry the pivots, and are held rigidly by the collars d^4 , called "ground rings". The construction and arrangement of the groups of line terminals may more readily be seen in Figs. 5, 6 and 7 of the drawing. Each group, in the present instance, comprises four rods d^1 , d^2 , d^5 and d^6 , of which d^1 and d^2 are terminals to which the two limbs of the associated telephone line extend, while d^5 is grounded or connected to earth, while d^6 is connected with a source of busy-tone current. The ground rings d^4 are metallically connected with the ground rod d^5 of each group, but are insulated from the other three rods. Mounted upon the line terminal rod d^1 of each group, but insulated therefrom, are a number of busy-tone rings d^3 , which are metallically connected by means of a part d^{10} extending from the ring (shown in Fig. 7) with the busy-tone rod d^6 of the associated group. The ground rings d^4 associated with each group are equal in number

to the pairs of connecting arms with which the switch mechanism is provided, and are so located as to be directly opposite and adapted to be engaged by a contact spring e^4 carried by the upper arm of each pair. The busy-tone rings d^3 are also equal in number to the pairs of connecting arms with which the switch is provided, and are so located as to be engaged, under certain conditions, by a contact spring f^3 , carried by the lower arm of each pair. As has heretofore been stated, each group d of terminals is pivotally mounted between the upper and lower segmental plates of the frame, the bearing for the upper pivot being preferably so formed in the end of a screw d^{12} provided with a lock nut d^{13} by means of which the bearing may be adjusted. As constructed in the present instance, the ground rod d^5 of each group coincides with the longitudinal pivotal axis of the group. Each group is provided with a retractile spring d^7 extending between the lower pivot plate of the group and a stationary abutment, and which serves to yieldingly hold the group in a position with its line terminal d^2 advanced toward the center of the switch and its line terminals d^1 , with the associated busy-tone rings d^3 retracted. The degree to which the group of terminals may be rotated by the spring d^7 is limited by the recovery stop d^8 associated with each group of terminals.

Within the cylindrical cage constituted by the groups of terminals d (I have illustrated fifty such groups in the present instance), a number of pairs of connecting arms E, F, are arranged to rotate. In the present instance, I have illustrated six pairs of arms, each pair being loosely mounted upon a shaft r^{13} rotatably supported along the longitudinal axis of the switch, and journaled in the bearings r^{14} , r^{15} in the bottom and top of the frame. The portion of the shaft r^{13} that carries the arms is insulated from the frame by means of short sections of insulating material r^{25} and r^{26} let into the shaft at its top and bottom. The shaft is rotated through the medium of the beveled gears r^{16} , r^{17} , the former of which is carried upon the shaft r^{13} , and the latter upon the counter-shaft r^{18} , journaled in the base r^{20} , and provided at its outer end with the pulley r^{19} by means of which power may be communicated to the shaft to cause its rotation.

As heretofore stated, each pair of arms is loosely mounted upon the rotatable shaft r^{13} , each pair being held between two collars r^{21} , r^{22} , rigidly secured to the shaft, friction between the collars and the hubs of the arms being prevented by the interposition of the ball bearings g^{10} , g^{11} (see Fig. 13). Ball bearings g^9 are also interposed between the two hubs g^8 and g^7 .

The construction of the pairs of connecting arms is illustrated in Figs. 5 through 14

of the drawings. Each arm, as constructed in the present instance, comprises two tubular electro-magnets secured to the hub of the arm, and extending radially therefrom in 5 opposite directions. The upper or finder arm E of the pair comprises the tubular magnets h and g, which extend from the hub g⁸ loosely mounted upon the central rotating shaft; while the lower or selector arm 10 F comprises the tubular magnets h and l extending radially from the hub l⁸. The magnets h and l of the arms E and F, respectively, are adapted to actuate devices which control the connection of their respective 15 arms with the rotating shaft, and other devices which anchor or clamp their respective arms to fixed points in the surrounding cylinder of terminal groups. The magnets g and l of the arms E and F, respectively, 20 serve to actuate switch parts which complete connection between the circuits of their respective arms and the groups of line terminals which surround them.

Referring more particularly to the upper 25 or finder arm E of the pair, the magnet h which extends from one side of the hub g⁸ and constitutes, with its associated parts, one-half of the arm, comprises a tubular shell h³ of iron within which extends an 30 iron core h⁶ (see Figs. 11 and 13), surrounded by a winding h¹. At the inner end of the magnet is an armature h² which is so constructed and related to the end of the pole-piece h⁶ as to permit of a considerable 35 range of movement. From the armature h² extends a key h⁸, which is adapted to engage a slot in the collar r²¹ fixed to the shaft r¹³, the arrangement being such that when the 40 armature is retracted the key engages the slot in the collar thus connecting the arm E with the rotating shaft. Another portion of the armature h² is adapted to engage and operate (through the medium, in the 45 present instance, of a lateral extension of the armature bearing an adjustment screw h¹⁵) a switch h¹⁴, the members of which are normally held in contact by the engagement of the armature with one of them, but which are adapted to separate when the armature 50 is attracted to the magnet. The extent of separation of the switch contacts is limited by the stop h¹³.

The armature h² of the magnet is carried upon the end of two side rods h⁴, which 55 have bearings at both ends in enlargements of the ends of the magnet shell h³ so as to be slidably movable therein, and which carry at their forward extremity, beyond the outer end of the magnet h, a yoke h⁷. 60 This yoke, as illustrated, is insulated from the rods h⁴, and carries upon an arbor h¹² extending between its extremities a loose sleeve to which is secured the fork or anchoring device h¹¹. The upper end of the 65 fork is pronged or bifurcated so as to em-

brace, when thrust forward, the pivot or ground rod d⁵ of any one of the groups of terminals opposite which it may come to rest. The lower end of the fork or anchor h¹¹ is journaled upon and insulated from 70 the end of a rod h¹⁶, the other end of which is journaled upon and insulated from an extension carried upon the outer end of the magnet shell h³. Encircling the two side rods h⁴ are helical compression springs 75 h⁵, interposed between the enlargement at the forward end of the magnet through which the rods pass, and sleeves secured to the rods. These springs normally serve to keep the armature h² in its retracted position, the key h⁸ in engagement with the slot in the fixed collar r²¹, and the fork or anchor h¹¹ out of engagement with the ground or pivoted rod of the encircling 80 groups of terminals. When the magnet h is energized, the key h⁸ is withdrawn and the fork h¹¹ is thrust forward to anchor the arm against further rotation.

The yoke which completes the magnetic circuit between the core h⁶ and the shell h³ of 90 the magnet h at its forward or outer end, is in the form of an armature h⁹ which is normally retracted, and which, when the magnet is energized, is actuated to complete the circuit between the contact rods h¹⁷ by 95 causing a contact plate h¹⁰ carried at its upper end to engage the ends of the contact rods, and thus close the circuit in which they are included.

Extending from the hub g⁸ of the upper 100 or finder arm E, and diametrically opposite the magnet h, is the connecting magnet g. This magnet is also of the iron-clad tubular type, and comprises an iron shell g³ within which is an iron core g⁶ surrounded by a 105 winding g¹. At the inner end of the magnet, or the end next the hub, is an armature g², so constructed and related to the pole of the magnet that it is capable of a considerable range of movement. The armature is carried at the ends of the two side rods g⁴ which have bearings in the enlarged 110 ends of the shell of the magnet g, so that they can slide longitudinally therein. Upon the outer ends of the side rods g⁴, and in 115 front of the forward end of the magnet g, is mounted an insulating block g⁷ in which are secured a number of contact springs that are adapted to make connection with the terminal rods of the groups which encircle 120 the arms. These comprise, in the present instance, the two line contact springs e¹, e², each of which comprises two metallic strips separated by a tongue of insulating material and having their outer ends turned outwardly to form a fork adapted to embrace 125 the terminal rod, and a test spring e³, which projects farther than the line springs e¹ and e², and is adapted, when the block g⁷ is in its retracted position, to make a wiping con- 130

tact with the advanced terminal rod d^2 of each group of terminals. The armature g^2 and the contact springs mounted upon the block which it controls, are normally held in their retracted position by helical compression springs g^3 which encircle the side rods g^4 , and are interposed between fixed collars carried upon said rods and the forward enlarged head of the magnet shell g^3 through which the rods pass. Upon the energization of the magnet, the armature is attracted, and the springs carried upon the block g^7 are thrust forward, the engagement of the contact spring e^2 with the advanced terminal rod d^2 of the opposite group of line terminals causing the group to turn upon its longitudinal axis, and thereby bring the terminal rod d^2 of the group forward and into engagement with the contact spring e^1 that has advanced to meet it. Connection between the contact springs carried on the block g^7 and other parts of the apparatus is completed through the medium of the connection rods g^{17} . Another insulating block g^{12} is carried upon the lower side of the outer enlarged head of the magnet shell g^3 , and upon it are mounted a contact spring e^4 , which is adapted to engage the corresponding ground ring d^4 of each group of terminals as the arm swings past it, and a contact spring e^5 which extends downwardly, and is adapted to engage a coöperating contact part f^5 carried upon the lower or selector arm F. The lower or selector arm F in its construction is, in general, similar to the upper or finder arm E. It comprises a movement controlling magnet h and a connecting magnet l extending radially and in opposite directions from a hub l^8 loosely mounted upon a rotating shaft r^{13} . As in the movement controlling magnet of the finder arm E, the magnet h of the lower or selector arm comprises a tubular iron shell h^3 , within which extends an iron core h^6 surrounded by a winding h^1 . The armature h^2 of the magnet, adapted to have a considerable range of movement, is carried upon the ends of the two side rods h^4 , which are slidably supported in the enlarged heads at the ends of the magnet shell h^3 , are provided with the encircling helical compression springs h^5 to keep the armature and its associated parts normally retracted, and carry upon their outer ends, and in front of the forward end of the magnet h , a yoke h^7 which serves to operate the fork or anchor h^{11} . The fork or anchor is fulcrumed upon the arbor or pivot rod h^{12} of the yoke, and has its lower extremity connected with the forward end of the magnet shell by means of the connecting rod h^{16} , insulating material being interposed at suitable points to effect the insulation of the fork or anchor from the metallic portions of the arm. As described in

connection with the movement controlling magnet of the upper arm E, the magnet l , through the medium of its armature, controls a key h^8 which, in the retracted position of the armature, engages a slot in the collar r^{22} fixed to the shaft, and also serves normally to keep the switch h^{14} with its contact parts together, the switch being permitted to separate its contacts when the magnet is energized and the armature attracted. 75

As described in connection with the arm h , the magnetic circuit between the core h^6 and the shell h^3 of magnet h is completed by an armature h^9 which is normally retracted, and which is actuated, when the magnet is energized, to complete the circuit between the contact rods h^{17} by causing the contact plate h^{10} carried at its upper end to engage the ends of the rods. 80

The construction of the connecting magnet l of the selector arm F is, in general, similar to that of the connecting magnet of the finder arm E. It comprises the tubular magnet consisting of an iron shell l^3 with a core l^6 , about which is placed the winding l^1 . The armature l^2 , adapted for a considerable range of movement, is carried upon the ends of the side rods l^4 , which are supported so as to slide in the enlarged heads of the magnet shell l^3 , are encircled by the compression springs l^5 to keep the armature normally in its retracted position, and carry upon their outer ends the insulating block 95 17 upon which the contact springs of the arm are mounted. The contact springs of the lower or finder arm comprise the line springs f^1 , f^2 , each consisting of two metallic strips with their ends bent outwardly to form a fork for grasping the terminal rod adapted to be engaged, and a busy test 100 spring f^3 , the outer end of which is bent downwardly to lie in a lower plane than the ends of the line springs, and is adapted to make contact with the associated busy tone ring d^2 of any of the groups of terminals when the group is rotated upon its axis to bring the busy tone ring forward. The rear end of the busy test spring f^3 is provided with an upwardly extending portion f^6 which, when the armature of the 105 magnet and the associated insulating block l^7 are retracted, lies in contact with the end f^4 of the middle one of the contact rods l^{17} , and is adapted to be separated therefrom when the insulating block with its associated 110 springs is thrust forward by the attraction of the armature. One of the outer ones of the contact rods l^{17} carries a contact part f^5 which is adapted to be engaged by the contact spring e^5 extending from the insulating 115 block g^{12} carried by the upper arm. 120

The two arms E, F together constitute a single connecting device, and in order to insure the continuity of the connecting circuits in all the positions of the arms, a com- 130

mutator m is provided through which the circuits between the arms are extended. This commutator comprises a number of concentric rings m^2 , m^3 , m^4 separated by insulating material, and upon which the brushes m^5 , m^6 and m^7 , respectively, bear. The commutator rings are secured to the hub of the lower or selector arm F , while the brushes are carried upon the upper or finder arm E . The brushes may be, as shown, in the form of curved springs, secured at their centers to connecting or terminal pieces, and with their ends bearing upon the contact rings. This construction is illustrated in Fig. 14, where the springs m^6 and m^7 are shown attached to the terminal pieces m^{10} , m^{11} , respectively, the terminal pieces being insulated from the hub upon which they are mounted.

Surrounding the outermost of the three commutator rings mentioned above, is a toothed ring m^1 , having as many teeth as there are groups of line terminals in the automatic switch with which the arms are associated. Coöperating with the toothed ring m^1 is a lever m^9 carried upon the hub g^8 of the upper arm, one end of which engages the teeth of the ring, and the other end of which is in position to operate a normally closed switch m^8 . This arrangement constitutes a circuit interrupter which becomes operative whenever the relative position of the two arms is changed, as the relative movement of the toothed wheel and the pawl portion of the lever m^9 which takes place at such a time causes the teeth as they pass beneath the end of the lever to raise and lower it, and thus to actuate the lever to make and break the circuit through the switch m^8 . Therefore, the revolution of the lower arm while the upper arm is stationary, or vice-versa, results in a series of interruptions of the current passing through the circuit in which the switch m^8 is included, the number of interruptions depending upon the extent of the relative movement of the arms, and the periodicity depending upon the rate of speed at which the arms move with relation to each other.

Referring now to Fig. 16, I shall describe the circuit connections of a pair of arms E , F , which together form a connecting device by means of which communication may be established between any two lines terminating upon the automatic switch. The connecting circuit proper comprises the conductors 5 and 6, the former of which extends from the line contact spring e^2 of the finder arm E to the line contact spring f^2 of the selector arm F by way of the commutator spring m^5 and the commutator ring m^2 ; and the latter of which extends from the contact spring e^1 of the finder arm E to the contact spring f^1 of the selector arm F , by way of the commutator spring m^6 and the commu-

tator ring m^3 . The windings of the magnets g and h of the finder arm E are connected in a bridge conductor 9 extending from the conductor 5 at a point between the contact e^2 and the commutator spring m^5 by way of the circuit interrupter m^8 . The connection of this conductor with the free pole of the battery p is made by way of the shaft r^{13} with which the inner end of the winding of the magnet h is connected, the shaft being in continual connection with the free pole of the battery by way of suitable commutator connections. The connection of the battery is restricted to the shaft r^{13} and the associated arms by means of the insulating portions interposed between the shaft and the bearings r^{14} , r^{15} , as mentioned heretofore, which prevent the flow of current from the battery to other parts of the framework. In order to avoid confusion in the connections the battery p is not shown connected with the shaft r^{13} in Fig. 16; but it will be understood that it is connected in the same manner as illustrated in Fig. 15.

The windings of the magnets h and l of the selector arm F are included serially in a conductor 10 which extends from the connecting circuit conductor 6 at a point between the contact spring f^1 and the commutator ring m^3 to earth or the grounded pole of the battery p by way of the commutator ring m^4 , the commutator spring m^7 , the conductor 11 and the ground spring e^4 of the finder arm E , which is adapted to make connection with the ground ring d^4 of an associated group of line terminals. A conductor 14 extends from the conductor 10 at a point between the windings of the magnets h and l to the contact point f^4 with which the busy test spring f^3 engages when the armature of the magnet l is in its retracted position. The circuit of the conductor 14 is adapted to be completed to earth, thus shunting the current from the winding of the magnet l , by the engagement of the busy ring d^1 of a group of terminals with the busy test spring f^3 , the circuit thereupon being completed to earth through the conductor 15 extending through the low resistance winding of an apparatus for applying the busy tone to the line. Another branch from the conductor 10, which includes the windings of the magnets h and l , extends by way of conductor 13 through the normally open contacts controlled by the armature h^9 of the magnet h and the normally closed contacts of the switch h^{14} , controlled by the other armature h^2 of the magnet h to the free pole of the battery by way of the shaft r^{13} . In like manner a branch circuit extends by way of conductor 12 from the connecting circuit conductor 5 to the earth connection made by the engagement of the ground spring e^4 with the ground ring d^4 , by way of the normally open contact controlled by the armature h^9

of the magnet h , the normally closed contacts of the switch h^4 controlled by the other armature h^2 of the magnet h , and the conductor 11.

5 Another branch circuit extends from the connecting circuit conductor 5 at a point between the contact spring f^2 and the commutator ring m^2 , by way of conductor 8 and the coöperating contacts e^5 , f^5 , of the upper and 10 lower arms to the wiping or test spring e^3 of the upper or finder arm E, the circuit being adapted to be completed by the contact of the test spring e^3 with the advanced terminal rod d^2 of a calling line.

15 Referring now more particularly to Fig. 15 of the drawing, I will explain the general circuit arrangement and organization of the entire system. Fig. 15 illustrates diagrammatically two telephone lines extending from 20 the substations A and B equipped with the special substation apparatus heretofore described, to a central office C where they are adapted to be connected by means of the automatic connecting devices described in 25 the foregoing. The substation A is connected with the central office by means of the conductors 1, 2 which extend to a group of terminals designated D and terminate upon the terminal rods d^1 , d^2 , respectively, 30 of the group. The substation B is connected with the central office by means of the two conductors 3, 4 which extend to a group of terminals designated D^1 and terminate upon the terminal rods d^1 , d^2 of the group.

35 The substation equipment at both stations is the same, and need therefore only be described in connection with one of the stations. The equipment comprises, in the present instance, the usual telephone transmitter, telephone receiver, induction coil and condenser connected in a circuit controlled by the usual telephone switch hook. In addition to the foregoing apparatus the circuit controlled by the switch hook includes one winding c^3 of a relay c , another winding c^2 of which is included in a conductor 18 which forms a permanently closed shunt of the contacts of the switch hook. The winding c^3 of the relay c , being serially 45 included in the talking circuit of the line, is made of low resistance, while the winding c^2 of the relay c , being in shunt of the switch hook contacts, and consequently serving to permanently close the circuit of the line 50 about the opening controlled by the switch hook, is made of high resistance.

The armature of the relay c controls, in its switch contact c^5 , the connection with earth of two conductors 19 and 17, the 60 former of which includes a resistance coil c^4 and extends from a normally open contact of the switch hook closed to form a branch to earth from the line when the hook is in its elevated position, and the latter of which 65 extends from the limb 1 of the line and in-

cludes the energizing coils of the telephone bell or ringer b . The telephone bell b is, as illustrated, of the "vibrating" type, and adapted to be energized by steady or continuous currents.

70 Associated with the line circuit, but normally disconnected therefrom, is the substation interrupter apparatus a . The circuit of the line extends through normally closed contacts of the switch a^{17} , while the interrupter circuit extends by way of the conductor 20 from the normally open contact of the switch a^{17} through the energizing coils a^{21} of the locking magnet of the switch a^{17} , the switch contacts a^{15} of the interrupter, 80 and the winding of the interrupter actuating magnet a^{11} . When the switch a^{17} is actuated the through circuit of the line is interrupted, the limb 1 of the line being left open in the contacts of the switch, and the limb 2 being extended by way of the conductor 20 through the switch and interrupter magnets a^{21} and a^{11} , respectively, to earth. The circuit thus completed, as will be seen, is subject to the control of the interrupter switch a^{15} , the manually operated and magnetically locked switch a^{17} , and the telephone switch hook of the substation.

85 The lines from the stations A and B, as has heretofore been stated, are connected at 90 the central office with the line terminal rods d^1 , d^2 of the terminal groups D, D^1 , respectively, of the automatic switch mechanism. The connections of the lines with the terminal rods of the groups are so made as not to 100 interfere with the oscillation of the groups upon their axes when the finder arms and selector arms make connection therewith.

95 The connecting circuit controlled by the finder arm E and the selector arm F of any 105 of the connecting devices, as has heretofore been traced, extends by way of the conductors 5 and 6 from the line contact springs e^2 , e^1 of the finder arm to the line contact springs f^2 , f^1 of the selector arm, with the 110 actuating magnets g and h of the finder arm E included together with the interrupter switch m^8 serially in a bridge 9 extending from the connecting circuit conductor 5 to the free pole of the central battery p ; while 115 the magnets k and l of the selector arm F are included serially in a bridge conductor 10 extending from the connecting circuit conductor 6 to the ground spring e^4 and co-operating ground ring d^4 . Associated with 120 the magnets of both arms are circuits 12 and 13, respectively, controlled in switch contacts of their respective magnets, which close a low resistance local circuit for the flow of current through the magnets at the 125 moment of their actuation. The shunt circuit about the magnet l to prevent its actuation, and to apply a busy tone through the connecting circuit to the line, is completed by way of the conductor 14 which is con- 130

trolled through the medium of the busy test spring f^3 and the coöperating busy tone rings d^3 of the groups of terminals. The busy tone rings of each group of terminals are connected to the busy tone rod d^6 , and the busy tone rods of all of the groups of terminals are connected by way of the common conductor 15 through one winding n^2 of an induction coil n to earth. The resistance of the winding n^2 is sufficiently low so that when the circuit in shunt of the magnet l is closed by way of the conductors 14 and 15 and the busy test spring f^3 and busy tone ring d^3 , the actuation of the magnet l is prevented. The other winding n^1 of the induction coil n is connected in a circuit with a battery p ,—which may, if desired, be the common battery which supplies current to the connecting circuits—and a device o which, by rapidly interrupting the circuit produced a tone inductively in the winding n^2 .

The operation of the system of my invention is as follows: We will assume that the subscriber at station A, whose telephone we may say is No. 1, wishes to call the subscriber at station B, whose telephone we will say is No. 25. The subscriber at station A first lifts his telephone receiver from the switch hook. This closes the circuit through the switch hook contacts, and connects the line with earth through the conductor 19, resistance coil c^4 and switch contact e^5 of the relay c . The finder arm test springs e^3 of the six pairs of connecting arms associated with the automatic switch R at the central office, are constantly making a wiping contact with the advance terminals d^2 of all of the unengaged groups of terminals; and consequently as soon as a test spring e^3 of any of the pairs of connecting arms makes contact with the terminal rod d^2 of the group D associated with the station A, a circuit is completed from the free pole of the central battery through the magnets g , h , of the finder arm E to earth at the calling substation, the circuit being traced by way of the conductor 9 including the magnets g and h and the normally closed interrupter switch m^8 to the connecting circuit conductor 5, thence by way of the conductor 8, the coöperating contacts f^5 , e^5 , of the upper and lower arms, (which are in engagement, the arms lying together in the same plane) the conductor 7, the test spring e^3 , the limb 2 of the line to the substation A, one of the windings of the substation induction coil, the transmitter, the switch hook contacts, the conductor 19, the resistance coil c^4 , and the relay contact c^5 . The current which immediately flows in this circuit causes the magnet h to withdraw its key from the rotating shaft r^{13} , and thrust its fork into engagement with the ground or pivot rod d^5 of the group of terminals immediately opposite the terminal

group of the calling line, thus arresting the movement of the finder arm and anchoring it at the point where it has stopped. At the same moment the energization of the connecting magnet g causes it to thrust its contact springs e^1 , e^2 , against the line terminal rods d^1 , d^2 , respectively, of the group D associated with the calling line A, the oscillation of the group upon its longitudinal axis causing the line terminal rod d^1 to be thrust forward to meet the contact spring e^1 . The operation of the magnets g and h is rendered more positive and reliable by means of the local circuit 12, which is closed to permit a strong initial current flow to pass through the windings of the magnets by the attraction of the armature h^9 , and is thereafter opened in the contacts h^{14} of the magnet by the attraction of the armature h^2 when it is moved to withdraw the key from the shaft, and anchor the arm.

The moment the contact terminals d^2 and e^2 come into engagement, a circuit is completed by which current flows from the free pole of the central battery through the magnets g and h over the limb 2 of the line to the substation, where a portion is diverted, because of the resistance c^4 interposed in the branch circuit to earth, through the low resistance winding c^3 of the relay c , serially interposed in the circuit of the line, and thence over the limb 1 of the line back to the central office, where it passes through the coöperating contacts d^1 , e^1 , and flows by way of the conductor 6 of the connecting circuit to the bridging conductor 10, and through the magnets h and l of the selector arm to earth by way of the ground spring e^4 and the ground ring d^4 . The effect of this current flow through the winding of the relay c is to cause it to open the switch contact e^5 , so that the branch from the line to earth by way of the conductor 19 is interrupted, and the circuit over which the conversation takes place thus becomes a metallic circuit free from earth connections. The current which flows in the metallic circuit of the line passes through the movement controlling magnet h of the selector arm F, and first causes the attraction of the armature h^9 which, in closing its contact, completes a low resistance local circuit through the magnet from the free pole of the central battery in shunt of the line circuit by way of the conductor 13. The maximum energization effected by the closure of this low resistance local circuit, causes the magnet h strongly to attract its armature, and, in so doing, to withdraw the associated key from the rotating shaft and thrust the associated fork h^{11} into engagement with the ground or pivot rod of the group of terminals opposite the group associated with the calling line, thus stopping the movement of the lower or selector arm. The magnet h , in attracting its

key and fork-controlling armature, also 5 interrupts the low resistance energizing circuit 13 in the switch contacts k^{14} controlled by this armature, thus leaving this magnet under the control of the circuit extending by way of the line to the substation A.

The connecting magnet l of the selector arm F would also be energized by the current that flows in the metallic circuit of the line, were it not for the existence of the low 10 resistance shunt about its winding completed over conductor 14 to earth by way of the busy test spring f^3 , the busy-tone ring d^3 , the common conductor 15, and the low resistance winding n^2 of the busy test induction 15 coil or transformer n . The connecting magnet l , under these conditions, is insufficiently energized to attract its armature, and therefore the contact springs f^1 , f^2 , f^3 , are not 20 brought into contact with the line terminal rods d^1 , d^2 .

It must be remembered that at this stage of the operation the arms of the pair have not separated, and lie with their connecting 25 springs opposite the same group of terminals,—namely, the group associated with the calling line A. The connecting magnet of the upper finder arm has been energized, as already explained, to thrust its contact 30 springs into engagement with the terminal rods of the group D; while the operation of the connecting magnet l of the lower or selector arm F has been prevented by the closing of the shunt circuit 14 and 15 about 35 the magnet by the thrusting forward and into contact with the busy test spring f^3 of the busy-tone ring d^3 , which results from the rotation upon its longitudinal axis of the group of terminals D.

40 The sequence of the actions thus far described is as follows. First, the magnets of the upper or finder arm are energized, for the energization of the magnets of the lower or selector arm depends upon engagement 45 between the contact springs e^1 , e^2 , of the upper arm and the line terminals of the calling line; second, the armatures of the magnets g and h of the upper arm are attracted, causing 50 the contact springs e^1 , e^2 of the upper arm to engage and turn the group of terminal rods of the calling line, a movement that thrusts the busy tone ring d^3 of that line into contact with the busy test spring f^3 of the lower arm; third, current passes over 55 the metallic circuit of the line and through the movement controlling magnet k of the lower arm, causing it to stop the movement of that arm, the current being diverted from the connecting magnet l by the shunt circuit 60 established by the engagement of the busy tone ring d^3 , with the busy test contact f^3 . Therefore, the selector arm operates precisely as if it were testing a busy line, as will be explained hereinafter. The advantage at this stage of the operation is that

the contact springs f^1 , f^2 are not allowed to touch the line terminal rods d^1 , d^2 , of the group D which are in engagement with the contact springs e^1 , e^2 of the upper or finder arm; if they were allowed to come in contact the cross connection of the contact springs f^1 , f^2 , of the connecting circuit with respect to contact springs e^1 , e^2 would connect all four magnets of the connecting arms in a closed bridge of the central battery, and 75 would thus lock both arms to the calling line.

At this stage of the operation both arms of the pair have been disengaged from the rotating shaft and anchored opposite the 80 group of terminals of the calling line, the contact springs of the upper or finder arm being in engagement with the line terminal rods, d^1 , d^2 . The subscriber now revolves the pointer arm a^4 of his interrupter until it 85 is opposite the number representing the desired line,—in this case number 25, the line extending to the substation B. This rotates the hub associated with the pointer arm and causes the spring of the switch a^{15} to ride 90 up out of the depression in the hub, and close the switch contacts. The subscriber then depresses the push button a^{19} which controls the switch a^{17} . This operates the switch to interrupt the metallic circuit of the 95 line, and to connect the limb 2 of the line to earth by way of the conductor 20, including the clutch magnet a^{21} of the switch a^{17} , the interrupter switch a^{16} , and the energizing magnet a^{11} of the interrupter. The establishment of this new circuit arrangement 100 causes the current which had heretofore flowed from the battery through the magnets g and h of the finder arm, to the substation, and back to the central office and through 105 the magnet k of the selector arm by way of limb 1 of the line, to be diverted to earth at the substation through the conductor 20 with its associated apparatus. The result 110 is that the magnets g and h of the finder arm remain energized, and retain that arm in contact with the terminals of the calling line, while the current flowing through the clutch magnet a^{21} of the switch a^{17} causes 115 the switch to remain in its operated position, thus diverting the line current from the magnet k of the selector arm. The resultant de-energization of the magnet k causes the withdrawal of the anchoring fork controlled by the magnet, the reengagement of the key with the rotating shaft n^{13} , and a resumption 120 of the revolution of the lower or selector arm F. The interrupter switch m^8 is so arranged that, as soon as the lower arm begins to move away from the upper arm, the line circuit is periodically interrupted, one break occurring for each group of terminal rods that the selector arm passes. Therefore, in progressing to the terminals of line No. 25 from line No. 1, the line circuit will be opened 125

and closed in the contacts of the interrupter switch m^8 , twenty-four times—the number of intervals between 1 and 25—and the actuating magnet a^{11} of the substation interrupter 5 a will be deenergized and energized a like number of times. The action of the armatures of all the magnets in this circuit is sluggish, excepting that of the magnet a^{11} of the interrupter, which is quick acting; 10 and the interruptions of the current flowing in the line produced by the action of the interrupter switch m^8 are too rapid to affect any of the armatures excepting that of the magnet a^{11} . Therefore, the latter armature 15 alone moves and, in so doing, causes the pointer arm a^4 to return in a contra-clockwise direction to its normal or home position, where it points to No. 1 on the dial, the return being effected by means of the reciprocating action of the escapement lever 20 a^8 on the star wheel a^7 , as heretofore described.

Consequently for every step which the selector arm F advances with relation to the 25 finder arm E, the pointer arm of the substation interrupter a returns one step, so that when the selector arm has advanced to the group of terminals associated with line No. 25, which is being called, the pointer 30 arm of the substation interrupter will have returned to its normal or home position, and the coöperating member of the interrupter switch a^{15} will have fallen into the depression in the hub a^{13} of the interrupter. This 35 causes the interrupter switch a^{15} to open the circuit which has heretofore existed through it and the magnets a^{21} and a^{11} from the limb 2 of the line. The interruption of the circuit through the clutch or locking magnet 40 a^{21} of the switch a^{17} causes the switch to return to its normal position, and the consequent closure of the metallic circuit of the line causes current to flow back over the limb 1 and through the movement controlling 45 magnet k of the selector arm F. The magnet k thereupon disengages the arm from the rotating shaft r^{13} and locks it in position with its contact springs opposite the terminals of the group upon which the line, No. 50 25, extending to substation B, terminates. It will thus be seen that the devices at the central office and at the substation exercise a reciprocal control over each other, the manually operated interrupter mechanism at the 55 substation bringing about the relative movement of the two connecting arms, this relative movement controlling the return movement of the interrupter mechanism, and the return of the interrupter mechanism limiting the advance movement of the selector arm.

If the called line, No. 25, is engaged, its group of terminals will be oscillated upon its axis to thrust the busy tone ring d^3 forward 60 so that when the selector arm F stops oppo-

site said group of terminals its busy test spring f^3 will be in contact with the busy tone ring d^3 , and the shunting circuit 14, 13 about the connecting magnet 1 of the arm will consequently be completed, so that the 70 arm will be prevented from thrusting its contact springs into engagement with the line terminal rods of the group. Moreover, the engagement of the contact spring f^3 with the busy tone ring d^3 will cause the tone 75 which is generated in the secondary winding n^2 of the busy tone transformer n to be transmitted by way of conductors 15 and 14 to the bridging conductor 10, whence a portion will flow to the connecting conductor 6 80 of the pair of arms and out over the circuit of the calling line to substation A, where it will be heard by the calling subscriber. This tone will indicate to the calling subscriber that the desired line is busy, and he will 85 thereupon replace his telephone receiver upon its hook.

If the called line, No. 25, is not engaged, the busy tone ring d^3 will be in its retired position, and consequently the shunt circuit 90 by way of conductor 14 is not established around the connecting magnet 1 of the selector arm when the arm comes to rest. The magnet 1 thereupon is operated by the current which flows over the circuit of the calling line 1, 2 to thrust its contact springs into engagement with the line terminals of the group upon which line No. 25 terminates. This causes the busy tone ring d^3 to advance 95 and make contact with the busy test spring f^3 , but this does not complete the shunt circuit of the connecting magnet 1, because the magnet, in thrusting forward its contact springs, has caused the forwardly extending tongue f^6 of the test spring f^3 to break contact with the pin f^4 against which it normally rests. In this way while the selector arm is prevented from making contact with a group of terminals made busy by engagement therewith of some other selector arm, 100 its actuation is not prevented by the change in condition of the group of terminals when brought about by its own operation.

If the called line, No. 25, is not engaged, the connecting magnet 1, as indicated above, 115 operates to thrust its contact springs into engagement with the terminals d^1 , d^2 of the line. It will be observed that the connection of the contact springs f^1 and f^2 of the selector arm with the central battery is such 120 that the free pole of the battery is applied, when the selector arm makes connection with a line, to the opposite limb of the line from that to which it is applied when the finder arm connects with the calling line. As a 125 result current flows from the free pole of the central battery by way of the conductor 5 of the connecting circuit to conductor 3 of the called line, and thence through the magnetizing coils of the bell b at the sub- 130

station B to earth by way of the normally closed contact of the relay c . This bell, as has heretofore been explained, is of the vibrating type which is adapted to be actuated by steady or direct current, and its armature is therefore operated to ring the bell until the called subscriber takes the telephone receiver from its hook. When this is done the current flows through the low resistance winding c^3 of the relay c at the called substation, interposed serially in the circuit completed by the closure of the contacts of the switch hook, and actuates the relay to open the switch contacts controlled by its armature. This interrupts the circuit to earth through the magnet windings of the bell, and stops the ringing. To prevent the bell from recommencing its ringing in case the called subscriber at station B should replace his receiver upon its hook while the connection with the line is still established at the central office, the relay c is provided with a high resistance winding c^2 , which, while insufficient in its power to cause the actuation of the relay switch contacts in the first place, is sufficient to maintain them in their operative position when once they have been actuated by the flow of current through the low resistance winding c^3 of the relay.

At the conclusion of the conversation the subscribers at the stations A and B replace their telephone receivers upon the switch hooks. The circuit over the lines through the finder arm magnets g and h and the selector arm magnets k and l is thus interrupted, and these magnets deenergized. The deenergization of the movement controlling magnets k and h causes the keys h^3 and h^8 , respectively, to press against their respective collars ready to engage the slots in the latter, when, in the course of their rotation, they pass beneath the waiting keys. Pending this reengagement the arms are held stationary by the engagement of the forks h^{11} and h^{11} , respectively, with the pivot or ground rods of the groups of terminals opposite those of the lines which the connecting magnets l and g have just permitted their contact springs to release. When the slots pass beneath the waiting keys, the keys fall into place, and the forks are simultaneously withdrawn from the pivot rods of the associated terminal groups, the key and the fork of each magnet being, by the construction employed, adapted to move together.

The two arms are now re-united, and ready to be appropriated by any other calling line. Until they are re-united, however, the separation of the contact spring e^5 , carried by the finder arm, from the contact pin f^5 , carried by the selector arm, interrupts the circuit to the test spring e^3 of the finder arm, so that the contacting of the test spring e^3 with the advanced terminal d^2 of any line that may be calling prior to the re-

uniting of the two arms of the pair is ineffective to energize the magnets of the finder arm to cause it to stop and complete connection with the calling line.

I have illustrated the automatic switchboard as being designed to accommodate fifty lines; but it is apparent that the mechanism may easily be constructed to accommodate as many or as few lines as it may be desired to serve. And where interconnecting means are to be provided for more lines than may conveniently be accommodated upon a single automatic switchboard such as that illustrated and described, a number of such switchboards or units may be employed, and caused to coöperate by means of interconnecting trunks in a manner familiar to these skilled in the art.

It will be apparent that various features which have been described in their application to the particular system shown, will be capable of application to other systems of widely different character. For example, I mention the feature of controlling the movement of a selector or other traveler by means of a controller located at a distant point and arranged to be operated by retractive current impulses transmitted back to such controller by a switch or interrupter operated periodically by the selector or traveler in its advance, the controller being adapted at the end of a predetermined movement, variable at will, to operate a switch which will cause the selector or traveler to be stopped. In the particular apparatus illustrated the stopping of the selector or traveler F is determined by the excitation of the clutch controlling magnet k which is caused to throw off the clutch when said magnet receives current over the bridge circuit reestablished by the switch a^{17} at the end of a predetermined movement of the controller a .

This feature of the invention may be more easily understood apart from its specific embodiment in the system shown in Fig. 15, by reference to Fig. 17, wherein the elements concerned in the selecting movement of the arm F are shown without reference to the other parts of the system. Fig. 17 shows a portion of the selector arm F which is adapted to be advanced by the continuously operating motor mechanism represented by the shaft r^{13} , under control of the clutch operating magnet k . When the magnet k is excited, as by current flowing from the battery p , over the metallic circuit of the line closed by the telephone switch at the substation and extending back through the magnet k , to earth at the selector, the clutch key is withdrawn from engagement with the rotating shaft 13 , and the arm F is stationary. The advance of the rotary arm F to any desired extent, as for the purpose of selection, is determined by the controller in

- the manner previously indicated, that is to say, the pointer arm a^4 is set ahead a given distance corresponding to the extent which it is desired that the distant selector arm F
- 5 shall be caused to travel. Now by depressing the push button a^{19} , its associated switch a^{17} is caused to open the metallic circuit, cutting off the return branch through the clutch controlling magnet k and substituting a ground branch through the controller which is closed by the switch a^{15} . The clutch being thus thrown on at the selector by the deenergizing of magnet k , the selector arm F is advanced by the continuously rotating shaft r^{13} , and the switch m^8 is periodically opened and closed during such advance, thus sending revertive impulses to the controller. The magnet a^{11} of the controller responds to these revertive impulses and steps the controller back to zero. The rapid pulsations of current in the circuit do not permit the sluggish magnet a^{21} to release its armature; but when the controller arm a^4 returns to zero, the switch a^{15} is opened, whereupon magnet a^{21} is deenergized, and switch a^{17} is restored, completing the bridge circuit of the line, and causing the clutch controlling magnet k at the selector to be excited. This will withdraw the key from the rotating shaft r^{13} , and stop the advance of the arm F; at the same time thrusting the fork k^{11} into engagement with the rod to which it has been advanced by the rotation of the arm F.
- 35 Although in the foregoing specification for the purposes of disclosure I have described apparatus and circuits of a specific character, it will be understood that my invention is not to be limited thereto, as it is obvious that equivalents may be substituted for various of the elements employed, the form of the parts may be changed, and the arrangement of the circuit altered as may be expedient under varying circumstances of use without departing from the spirit or scope of my invention and claims.
- I claim:
1. The combination with a plurality of telephone lines extending to a central office, of a switch having relatively stationary terminals whereon said lines terminate, and a plurality of pairs of independently movable switch arms coöperating with the same terminals, each of said pairs being adapted to connect together any two of said lines.
2. The combination with a plurality of telephone lines extending to a central office, of a switch having relatively stationary terminals whereon said lines terminate, means for connecting said terminals comprising a pair of independently movable switch arms, means for causing said arms to traverse and make contact with the aforementioned stationary terminals, and mechanism
- adapted to stop the movement of said arms and cause one of them to complete connection with the terminals of any predetermined line.
3. The combination with a plurality of telephone lines extending to a central office, of a switch having relatively stationary terminals whereon said lines terminate, a plurality of pairs of switch arms, means for causing said pairs of arms to traverse and make contact with said stationary terminals in succession, and mechanism adapted to stop the movement of any pair of said arms and cause one arm of the pair to complete connection with the stationary terminals associated with any given line.
4. The combination with a plurality of telephone lines extending from their respective substations to a central office, of a switch having stationary terminals whereon said telephone lines terminate, connecting means comprising a pair of switch arms adapted to traverse and make contact with said line terminals, means for causing the movement of said arms, mechanism made operative in initiating a call in any one of said lines adapted to arrest the movement of said arms and cause one of them to complete connection with the terminals of said line.
5. The combination with a plurality of telephone lines, each extending from its respective substation to a central office, of a switch having stationary terminals whereon said lines terminate, a plurality of pairs of switch arms, each pair being adapted to complete connection between any two of said telephone lines, means for normally causing said arms continually to traverse the terminals of said lines, means adapted in initiating a call in any of said lines to change the condition of its associated switch terminal, and mechanism associated with each pair of switch arms adapted to arrest the movement thereof, said mechanism being responsive to the changed condition of the terminal of the calling line.
6. The combination with a plurality of telephone lines extending to a central office, of a switch having stationary terminals whereon said lines terminate, connecting means for said switch comprising a finder arm and a selector arm interconnected and independently movable on a common support, and means adapted to move said arms with said support to complete connection between the terminals of any two of said lines.
7. The combination with a plurality of telephone lines extending to the stationary contacts of a switch at a central office, of connecting means comprising a finder arm and a selector arm, said arms being interconnected and independently movable, means for normally continuously rotating

said arms to traverse said stationary terminals, means made operative in initiating a call from one of said lines adapted to stop the finder arm and cause it to make connection with the terminals of the calling line, and means adapted to cause the selector arm to complete connection with the terminals of another line.

8. The combination with a plurality of 10 telephone lines extending from their respective substations to a central office, of a switch having stationary terminals whereon said lines terminate, connecting means comprising a finder arm and a coöperating and independently movable selector arm, means for causing the movement of said arms relatively to said stationary terminals of the switch, means made operative in initiating a call in one of said lines adapted to stop 15 the movement of both arms and cause the finder arm to make connection with the calling line, and means controlled from the substation of said calling line adapted to cause a further movement of said selector arm to 20 complete connection with the terminals of another line.

9. The combination with a plurality of 30 telephone lines extending from their respective substations to a central office, of a switch having terminals whereon said lines terminate, connecting means comprising a pair of traveling switch members adapted to traverse the same terminals, means for moving said members, means adapted to 35 cause one of them to complete connection with the terminals of a certain line, and means controlled through the medium of the line with whose terminals connections are made adapted to cause the other to complete connection with the terminals of another line.

10. The combination with a calling line and a called line extending from their respective substations to the terminals of a 45 switch at the central office, of connecting means comprising a finder arm and a selector arm, means for causing said arms to traverse said terminals, electrically actuated mechanism adapted to stop the movement 50 of said arms, a switch at the substation of the calling line adapted to control the actuation of said stopping mechanism to bring said arms to rest at the terminals of the calling line, and means controlled from the 55 calling substation adapted to cause the continued movement of the selector arm to complete connection with the terminals of the called line.

11. The combination with a plurality of 60 telephone lines extending to the terminals of a switch, of connecting means comprising a finder arm and a coöperating and independently movable selector arm, means for causing the movement of said arms with relation to said terminals, said selector arm

being adapted to be advanced independently of said finder arm, and a device made operative in the independent advance of said selector arm adapted to control the movement of said arm.

12. The combination with a plurality of 70 telephone lines extending to the stationary terminals of a switch, of connecting means comprising a finder arm and a coöperating selector arm, means for causing said arms to traverse said stationary terminals, said selector arm being adapted to be advanced independently of said finder arm, mechanism adapted to stop the advance of said selector arm, and a device made operative in the independent movement of said selector arm adapted to control said stopping mechanism.

13. The combination with a plurality of 75 telephone lines extending to the terminals of a switch, of connecting means comprising 80 a finder arm and a coöperating selector arm, means for causing said arms to traverse said line terminals, mechanism associated with each arm adapted to stop its movement, and a device rendered operative in the movement 85 of the selector arm relative to the finder arm adapted to control the stopping mechanism associated with the selector arm.

14. The combination with a plurality of 90 telephone lines extending from their respective substations to a central office, of a switch having terminals whereon said telephone lines terminate, connecting means comprising a finder arm and a coöperating selector arm, means for causing said arms to move 95 together and traverse said line terminals, means adapted to arrest the movement of said finder arm and cause the same to make connection with the terminals of one of said lines, mechanism for stopping the movement 100 of said selector arm, a device at the substation of the line with which the finder arm has made connection adapted to control the stopping mechanism of said selector arm, and means made operative in the movement 105 of said selector arm relative to said finder arm adapted to control said substation device.

15. The combination with a plurality of 110 telephone lines extending from their respective substations to a central office, of a switch having stationary terminals whereon said lines terminate, connecting means comprising 115 a finder arm and a coöperating selector arm, means for causing said arms to traverse said stationary terminals, mechanism associated with the finder arm adapted to stop the same and cause it to complete connection with the terminals of one of said lines, mechanism associated with the selector arm, 120 adapted to stop said arm and cause it to complete connection with the terminals of another line, an electrically actuated step-by-step device at the substation of the line with whose terminals said finder arm has made 125 130

connection adapted to control said stopping mechanism, and a switch made operative in the movement of said selector arm relative to said finder arm adapted to control said 5 step-by-step device.

16. The combination with a plurality of telephone lines extending from their respective substations to a central office, of a switch having stationary terminals whereon said 10 lines terminate, connecting means comprising a finder arm and a coöperating selector arm, means for causing said arms to move together and traverse said stationary terminals, mechanism associated with the finder 15 arm adapted to stop the same and cause it to complete connection with the terminals of one of said lines, mechanism associated with the selector arm adapted to stop said arm and cause it to complete connection with the 20 terminals of another line, a manually set switch at the substation of the line with whose terminals the finder arm has completed connection, said switch being adapted to control the aforesaid mechanism, an electro-magnet controlling the restoration of 25 said substation switch, and a switch made operative in the movement of said selector arm relative to said finder arm adapted to control the actuation of said substation electro-magnet.

17. The combination with a plurality of telephone lines extending from their respective substations to a central office, of a switch having stationary terminals whereon said 30 lines terminate, connecting means comprising a finder arm and a coöperating selector arm, means adapted to cause said arms to move together and traverse said terminals, means for arresting the movement of the 35 finder arm and causing it to complete connection with the terminals of one of said lines, a switch actuated by a movement of said selector arm relative to said finder arm and adapted to produce pulsations of current in the circuit of the line with the terminals of which the finder arm has made 40 connection, an electrically actuated step-by-step device at the substation of said line adapted to respond to said pulsations of current, said device being adapted to alter the 45 circuit of said line at the end of a predetermined number of pulsations variable at will, and mechanism adapted to stop the movement of said selector arm and cause the same to complete connection with the terminals of another line, said mechanism being responsive to the altered condition of said line caused by the operation of said substation 50 step-by-step device.

18. The combination with a plurality of telephone lines extending from their respective substations to a central office, of a switch having stationary terminals whereon said lines terminate, connecting means normally 55 unconnected with said lines comprising a

finder arm and a coöperating selector arm, means adapted to cause said arms to traverse said stationary terminals of the switch, a magnet associated with each of said arms for stopping the movement thereof, an actuating circuit for said magnets, and a switch at the substation of one of said lines adapted to control said actuating circuit.

19. The combination with a plurality of telephone lines extending from their respective substations to a central office, of a switch having stationary terminals whereon said lines terminate, connecting means normally unconnected with said lines comprising a finder arm and a coöperating selector 75 arm, means adapted to cause said arms to traverse said stationary terminals of the switch, a magnet associated with each of said arms for stopping the movement thereof, an actuating circuit for said magnets, and a switch mechanism at the substation adapted to control said actuating circuit, said switch mechanism being adapted to cause the actuation of said stopping magnets at different times, whereby said arms are caused to complete connection with the terminals of different lines.

20. The combination with a plurality of telephone lines extending from their respective substations to a central office, of a switch 95 having stationary terminals whereon said lines terminate, connecting means comprising a finder arm and a coöperating selector arm, means adapted to cause said arms to traverse said stationary terminals of the 100 switch, a magnet associated with each of said arms for stopping the movement thereof, an actuating circuit for said magnets, a switch at the substation adapted to be manually operated to complete the actuating circuit through the magnet of the finder arm while leaving the magnet of the selector arm inert, whereby the selector arm is advanced to the terminals of another line, and automatically actuated mechanism adapted to 105 restore said substation switch to complete the actuating circuit through both stopping magnets.

21. The combination with a plurality of telephone lines extending from their respective substations to a central office, of a switch 115 having stationary terminals whereon said lines terminate, connecting means associated with said switch comprising a finder arm and a selector arm, means for causing said 120 arms to traverse said stationary terminals, electromagnetic mechanism associated with each arm adapted to stop the movement thereof and cause the arm to complete connection with certain of said stationary terminals, a switch at said substation adapted when operated to actuate the stopping mechanism of both arms, another switch at said substation adapted when operated to maintain the actuation of the magnet of the 125 130

- finder arm and render the magnet of the selector arm inert, an electrically actuated device at the substation adapted to restore said last mentioned switch to its normal condition after it has been operated, and a switch made operative in the movement of the selector arm relative to the finder arm for controlling said electrically actuated device at the substation.
- 10 22. The combination with a plurality of telephone lines extending from their respective substations to a central office, of a switch at the central office having stationary terminals whereon said lines terminate, connecting means comprising a finder arm and a coöperating selector arm each provided with contact members, a magnet for each arm adapted to thrust said contact members into engagement with the stationary terminals of a calling and a called line respectively, means for causing said arms to traverse said stationary terminals, an actuating circuit for said magnets, and switch mechanism at the substation of each line adapted 25 to control said actuating circuit.
23. The combination with a plurality of telephone lines extending from their respective substations to a central office, of a switch having stationary terminals whereon said lines terminate, connecting means comprising a finder arm and a coöperating selector arm each provided with contact members, a magnet for each arm adapted to thrust said contact members into engagement with the stationary terminals of any of said lines, an actuating circuit for said magnets, switch mechanism at the substation of each line adapted to control said actuating circuit, other means for making connection with the 30 terminals of any of said lines, and means made operative in the completion of such other connection adapted to prevent the energization of the connecting magnet of the selector arm.
- 45 24. The combination with a telephone line extending from its substation to a central office, of a switch having a movable arm whereon said line is adapted to terminate, other telephone lines terminating on stationary contacts of said switch, a magnet associated with said arm and adapted to cause the same to establish connection between the telephone line associated therewith and another line terminating on said stationary terminals, an actuating circuit for said magnet, switch mechanism at said substation adapted to control said actuating circuit, other means for completing connection with the terminals of any of said lines, the position of such terminals being altered by the completion of connection therewith, and a device responsive to such altered position of the terminal of a line adapted to prevent the actuation of the connecting magnet of the 50 switch.
- 55 25. The combination with a telephone line extending to a central office, of a switch having a movable arm whereon said line is adapted to terminate, other telephone lines terminating upon terminals of said switch wherewith said movable arm is adapted to coöperate, a terminal of each of said lines being adapted to have its position altered when connection is completed with its associated line, means for causing said arm to traverse said terminals, a magnet adapted to cause said arm to complete connection with any of said lines at the associated terminals thereof, an actuating circuit for said magnet, and means made operative through the altered position of the terminal of an engaged line adapted to prevent the actuation of the connecting magnet to cause the associated arm to complete connection with said line.
26. The combination with a plurality of telephone lines extending from their respective substations to a central office, of a switch having a plurality of movable connecting members whereon said lines severally are adapted to terminate, other telephone lines extending to terminals of said switch wherewith said connecting members are adapted to coöperate, means for causing said connecting members to traverse said terminals of the switch, a connecting magnet for each connecting member adapted when actuated to cause said member to complete connection with a terminal of one of said other telephone lines, said terminals being movably mounted and adapted to be slightly displaced when one of said connecting members completes connection therewith, an actuating circuit for each of the aforesaid connecting magnets adapted to be controlled in the substation of the line with which said member is associated, a neutralizing circuit for each of said magnets adapted to prevent the operation thereof, and coöperating switch parts adapted to control said neutralizing circuit, one of said parts being carried on the arm and the other part being associated with the terminals of each line, and adapted to be moved into position when connection has been completed with the line, to engage the coöperating part of another arm attempting to make connection with the line, and prevent the actuation of its connecting magnet.
- 60 27. The combination with a plurality of telephone lines extending from their respective substations to the stationary terminals of a switch at the central office, of a telephone switch at the substation of each line adapted to close the circuit of the line thereat, a pair of connecting members adapted to coöperate with said stationary terminals,

- means for causing said members to traverse said terminals, a contact part associated with one of said members adapted to make contact with a terminal of each line as the 5 member traverses said terminals, electrically actuated mechanism adapted to stop the movement of said members, said mechanism being responsive to the simultaneous closure of the telephone switch at the substation of 10 any of said lines and the engagement of the contact part of said switch member with the stationary terminal of the corresponding line, and means controlled by the line thus engaged adapted to cause the other member 15 of the pair to complete connection with the terminal of another line.
28. The combination with a telephone line extending from its substation to a relatively stationary terminal of a switch at the 20 central office, of a plurality of relatively movable switch arms associated with said switch, said arms being adapted to traverse said terminal in succession and make momentary contact therewith, electrically actuated mechanism associated with each arm 25 adapted to cause the arm to stop and complete connection with the terminal of the line, said mechanism being responsive to the initiation of a call in any one of said lines, 30 and a movable mounting for the terminal of each line, whereby an arm in completing connection with any one of said terminals moves the same out of the path of contact of the other arms.
35. The combination with a plurality of telephone lines extending from their respective substations to the relatively fixed terminals of a switch at a central office, of connecting means comprising a plurality 40 of pairs of switch arms adapted to be moved to make contact periodically with the terminal of each of said lines, means for moving said arms, electrically actuated mechanism associated with the arms adapted to 45 arrest the movement thereof and cause the same to complete connection between any two of said lines, and means controlled from the substation of each of said lines adapted to render operative said electrically actuated 50 mechanism.
30. The combination with a plurality of telephone lines each extending in two limbs from its respective substation to a central office, of a switch having a plurality of pairs 55 of terminals whereon said lines respectively terminate, connecting means comprising a pair of movable switch arms adapted to co-operate with said terminals, each of said switch arms being provided with a two conductor connecting circuit extending there- 60 through and terminating at each end on two contact parts adapted to co-operate with the terminals of said lines, means for causing said arms to traverse said terminals, an elec- tro-magnet associated with each arm and 65 adapted to stop the movement thereof and cause the associated contact parts to engage the terminals of one of said lines, and a bridge of said connecting circuit including the windings of said magnets together with 70 a source of current.
31. The combination with a plurality of telephone lines each extending in two limbs from its substation to a central office, of a switch having a plurality of pairs of terminals whereon said lines respectively terminate, connecting means comprising a pair of arms adapted to co-operate with said line terminals, said arms being provided with a two conductor connecting circuit extending 75 therethrough and terminating at each end on two contact members, means for causing said arms to traverse said line terminals, an electro-magnet associated with each arm adapted to stop the movement thereof and cause the associated contact parts to engage the terminals of one of said lines, a bridge of said connecting circuit including the windings of said magnets together 80 with a source of current, a call signal device associated with each line at the substation thereof, said device being adapted to respond to the current from the aforesaid source when applied to the line in a particular manner, and means, made operative in the actuation of one of said arms to complete connection with a called line, adapted to apply current from said source to said line in the manner to operate said call signal device.
32. The combination with a plurality of telephone lines extending from telephone switches at their respective substations to a central office, of a switch having stationary terminals whereon said lines terminate, a movable switch arm adapted to co-operate with said terminals, means for causing said arm to traverse said terminals, electro-magnetic mechanism associated with said arm adapted to stop the movement thereof and cause the arm to complete connection with the terminals of one of said lines, an actuating circuit for said magnetic mechanism completed in the closure of the telephone switch at the substation of any of said lines, switch contacts operated by said magnet, and a branch of said connecting circuit in shunt of said telephone switch extending through said switch contacts and closed momentarily in the actuation of said magnet to increase the excitation thereof.
33. The combination with a telephone line extending from its substation to a central office, of a switch having stationary terminals on one of which said line terminates, a movable switch member adapted to traverse said terminals and make momentary contact with a terminal of said

line, means for moving said switch member, means adapted to change the electrical condition of said contacted terminal in the act of initiating a call in the line, a magnet associated with said member and adapted to stop the movement thereof and cause said member to make continuous connection with said line, an actuating circuit for said magnet responsive to the altered electrical condition of the terminal of said line as the movable member makes momentary contact therewith, means for extending the connection from said movable switch member to another line, and a switch made operative in the extension of said connection adapted to make inoperative said actuating circuit.

34. The combination with a plurality of telephone lines extending from their respective substations to a central office, of a switch having stationary terminals whereon said lines terminate, a movable switch member adapted to traverse said terminals and make momentary contact therewith, means for moving said switch member, means made operative in initiating a call in any of said lines adapted to alter the electrical condition of a switch terminal thereof, a magnet associated with said movable switch member and adapted to stop the movement thereof and cause the member to make continuous connection with one of said lines, an actuating circuit for said magnet responsive to the altered electrical condition of the terminal of a calling line, said actuating circuit being adapted to be completed in two branches, one of said branches being momentarily extended to a terminal of each line as the movable member traverses said terminals, and the other branch being continuously completed to the terminal of any line with which connection is completed, means for extending the connection from said movable member to another of said lines, and a switch actuated in the extension of said connection to open said first mentioned branch of the actuating circuit of said magnet, whereby said branch is rendered inoperative to effect the actuation of said stopping magnet while the connection of said movable switch member is extended to another line.

35. The combination with a plurality of telephone lines extending from their respective substations to a central office, of a switch having stationary terminals whereon said lines terminate, connecting means comprising a finder arm and a coöperating selector arm coöperating with said stationary terminals, said arms being arranged to move together normally but being adapted to be moved independently, means for effecting the movement of said arms, a magnet associated with each arm adapted to stop the

movement thereof and cause the arms to complete connection with the terminals of one of said lines, an actuating circuit for said magnet, and a switch actuated in the separation of said arms due to their independent movement to render inoperative said actuating circuit.

36. The combination with a plurality of telephone lines extending from their respective substations to a central office, of a switch having stationary terminals whereon said lines terminate, means associated with each of said lines adapted to change the electrical condition of a terminal associated therewith in the act of initiating a call, a movable switch member adapted to traverse said stationary terminals, electrically actuated mechanism responsive to the changed electrical condition of said terminal of a calling line and adapted to operate to cause said switch member to stop and complete connection with said line, means for extending the connection from said movable switch member, an actuating circuit for said electrically actuated mechanism, and a switch for controlling said actuating circuit, said switch being actuated to render said circuit inoperative in extending the connection from said movable switch member.

37. The combination with a plurality of telephone lines each extending from a circuit controlling switch at its substation to the stationary terminals of a switch at a central office, connecting means comprising a finder arm and a selector arm, means for moving said arms, a magnet associated with each of said arms adapted to stop the movement thereof and cause the arm to complete connection with the terminals of one of said lines, an actuating circuit for said finder arm magnet terminating upon a switch part adapted to make momentary contact with a terminal of each line as the finder arm traverses the same, said actuating circuit being completed and said finder arm magnet energized by the closure of the substation switch of one of said lines during the engagement of said contact part with the corresponding switch terminal of said line, and a switch associated with said arm and controlling said actuating circuit, said switch being operated to open said actuating circuit by the separation of said selector arm from said finder arm after the finder arm has been stopped.

38. The combination with a telephone line extending in two limbs from a substation to suitable terminals at a central office, the circuit of said line being normally open at both ends, of a branch from said line to earth or a return conductor at the substation thereof, a telephone switch at the substation adapted to complete connection between said branch and one limb of the line, an auto-

- matic switch device adapted to traverse the terminals of said line at the central office, and to make momentary connection with the terminal thereof associated with the 65
- 5 limb of the line adapted to be connected to ground by the operation of said substation telephone switch, a magnet associated with said switch device and adapted when actuated to cause said device to complete connection with the terminals of said line, an actuating circuit for said magnet adapted to be completed by way of said grounded limb of the line when the telephone switch is operated, and a relay at the substation actuated when said device completes connection with the line, and adapted to open said grounded branch at the substation, said actuating circuit being thereafter completed by way of the other limb of the line.
- 10 39. The combination with a telephone line adapted to terminate upon the movable member of a switch at a central office, of other lines terminating upon terminals of the switch wherewith said movable member is adapted to coöperate, means for completing connection with the terminals of any of said lines, said terminals being movably mounted so as to be slightly displaced when said connecting means operates to complete 15 connection therewith, means for causing said movable member of the switch to traverse the line terminals thereof, a magnet associated with the movable member and adapted when actuated to stop the movement thereof and cause said member to complete connection with the terminals of any of said lines, a neutralizing circuit for said magnet adapted to prevent the actuation thereof, and switch mechanism for controlling said 20 neutralizing circuit, said mechanism being adapted to be actuated by the displacement of the terminals of an engaged line to close said neutralizing circuit, and by the operation of the magnet associated with said 25 movable member to open said neutralizing circuit.
40. The combination with a telephone line extending from its substation to a central office, of a switch having a terminal whereton 30 said line terminates, a plurality of movable members adapted to coöperate with said terminal, means for moving said members to make momentary contact with said terminal in succession, electrically actuated mechanism associated with each switch member and adapted when actuated to arrest the movement of said member and cause the same to complete connection with said terminal, said terminal being adapted by the 35 completion of connection therewith to be moved out of the path of contact of the other movable members, a source of busy test current, and a switch part connected therewith and moved by the displacement of said 40
41. The combination with a telephone line extending from its substation to a central office, of a switch having a terminal part whereton 45 said line terminates, said terminal part comprising a group of metallic rods mounted to oscillate about the longitudinal axis of the group and normally held with one of said rods in advance of the other, a plurality of switch arms adapted to coöperate with said terminal group, said switch arms being adapted to engage said group at different points along the length thereof, means for causing said switch arms to traverse said group one after the other and make momentary connection with said advanced rod, and electrically actuated mechanism associated with each arm and adapted to stop the movement thereof and cause the arm to thrust its contact parts into engagement with said rods, the group of terminal rods being thereby oscillated to move the advanced rod out of the path of contact of the other switch arms.
42. The combination with a telephone line extending from its substation to a central office, of a switch having a terminal part whereton 50 said line terminates, said terminal part comprising a group of metallic rods mounted to oscillate about the longitudinal axis of the group and normally held with one of said rods in advance of the other, a plurality of switch arms adapted to coöperate with said terminal group, said switch arms being adapted to engage said group at different points along the length thereof, means for causing said switch arms to traverse said group one after the other and make momentary connection with the advanced rod thereof, a source of busy test current, a plurality of contact parts connected therewith and carried upon one of said rods adapted to be swung forward as the group is 55 oscillated by the completion of connection therewith, and a coöperating contact part carried upon each switch arm and connected with the circuit thereof, said part being adapted to receive busy test current as the associated arm is moved into position to complete connection with the group where-with another arm has made connection.
43. The combination with a plurality of telephone lines extending from their respective substations to a central office of a switch having a plurality of groups of terminals whereton 60 said lines terminate, each of said groups comprising a number of metallic rods insulated from each other and mounted to oscillate about the longitudinal axis of the group, one of said rods being normally held in a position in advance of the others, a

plurality of switch arms adapted to co-operate with said groups of terminals and to engage the same at different points along their length, means for causing said arms to traverse said terminals, each arm having a contact part adapted to make momentary connection with the advanced terminal rod of a group as the arm traverses the same, an electro-magnet associated with each arm adapted to stop the movement thereof and cause said arm to complete connection with one of said groups, and an actuating circuit for said magnet completed in the engagement of the aforesaid contact part of the arm with the advanced terminal of a calling line, said group being adapted to be oscillated by the completion of connection therewith to move said advanced terminal rod back out of the path of movement of the contact parts of the other switch arms.

44. In a telephone system, the combination with a subscriber's line, a normally open switch at the substation thereof and an electromagnet at the central office adapted to be included in the circuit of said line, of a contact device controlled by said electromagnet and adapted to extend the circuit of said

line, switching mechanism controlled by said electromagnet, and a branch in shunt of said line adapted to be closed momentarily by said switching mechanism in the actuation of said electromagnet to increase the excitation thereof. 30

45. In a telephone system, the combination with a subscriber's line, a stationary 35 switching terminal therefor and a movable contact device, of an electromagnet associated with said contact device and adapted to maintain a connection to extend the circuit of said line when once established between said terminal and said contact device, a switch at the substation of said line, said electromagnet being energized by current in said line when said substation switch is closed, a branch in shunt of said line and switching mechanism adapted to close momentarily said branch upon the energization 40 of said electromagnet to increase the excitation thereof. 45
